SHEET ANNEALING FURNACE

Application filed April 6, 1928; Serial No. 267,827.

The present invention relates to annealing furnaces wherein sheet material is continuously passed through a desired heat treating process. The object of my invention is to provide an improved construction and arrangement of an annealing furnace of this type and the material carrying means associated therewith.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described preferred embodiments of the invention.

Of the drawings:

Fig. 1 is a diagrammatic plan view of one embodiment of my invention;

Fig. 2 is a diagrammatic elevation of the apparatus of Fig. 1;

Fig. 3 is a section on the line 3—3 of Fig. 1;

Fig. 4 is a section on the line 4—4 of Fig. 1;

Fig. 5 is a section on the line 5—5 of Fig. 1;

Fig. 6 is a section on the line 6—6 of Fig. 1;

Fig. 7 is a section on the line 7—7 of Fig. 1;

Fig. 8 is a section on the line 8—8 of Fig. 1;

Fig. 9 is an enlarged elevation of the carrier of my invention;

Fig. 10 is an end view of the apparatus shown in Fig. 9;

Fig. 11 is a section on the line 11—11 of Fig. 9;

Fig. 12 is a vertical section through the burner section of a furnace having a modified form of carrier;

Fig. 13 is a similar section showing a modified arrangement;

Fig. 14 is a view similar to Fig. 13 of a fourth arrangement;

Fig. 15 is a diagrammatic plan view of the arrangement shown in Fig. 14;

Fig. 16 is an enlarged view of the sheet material holding means of Fig. 12; and

Fig. 17 is a view showing a modified form of sheet material holding means.

In Figs. 1 and 2 of the drawings I have diagrammatically illustrated a preferred em-

bodiment of my invention in which a horizontal annealing furnace A comprises a combined preheating and heating zone *a* and a cooling zone *b* longitudinally arranged along the furnace. Sheets of metallic material are suitably supported on an endless carrier B are passed into the entrance end A' of the furnace, through the preheating and heating sections wherein they are heated to a desired temperature and after being cooled in the cooling section *b* are passed out through the exit end A². Sprocket wheels C and C' are positioned at points longitudinally spaced from the opposite ends of the furnace for regulating the movement of the endless conveyor B. As illustrated in Fig. 1 one run of the conveyor passes through the furnace A while the return run passes externally of the furnace. A loading platform D is positioned between the sprocket wheel C and the entrance end A'. At the opposite end of the furnace and positioned between that end and the sprocket C' is an unloading platform E where the sheet material is removed from the conveyor.

The annealing furnace is substantially rectangular in cross-section with a vertical furnace chamber A³ extending the entire length of the furnace. The heating and cooling sections of the furnace chamber have a width approximately half of the height and are enclosed by vertical refractory walls A⁴ reinforced at their outer sides by a structural steel frame F. The upper end of the furnace chamber is tapered and connected to the atmosphere by a narrow slot A⁵ extending the length of the furnace. A longitudinal metallic trough A⁶ is mounted on the top of the furnace at each side of the slot A⁵. The frame F comprises vertical beams F', F² and F³ connected by horizontal cross beams F⁴. A longitudinal steel framework F⁵ is arranged on the top of the furnace and suitably braced from the vertical beams F' and F².

In the combined preheating and heating section *a* are arranged upper and lower series of longitudinally spaced burner nozzles G, each of which is positioned in a horizontal passage G' in the chamber side wall sealed 100

- at its outer end. The inner end G^2 of each nozzle is tapered and turned downwardly to discharge a combustible mixture of gas and air into the furnace chamber. The portion of the side wall of the chamber adjacent the discharge end of the upper nozzles projects inwardly and upwardly to form a small vertical baffle H for deflecting the combustible gases into the upper half of the furnace chamber.
- 10 The lower series of nozzles discharge against an adjacent recessed block H' in the floor of the combustion chamber which deflects the burning mixture upwardly. The nozzles are preferably arranged on both sides of the furnace chamber and provide a uniform heating effect throughout the height of the chamber. A control valve G^3 is provided for each burner nozzle for regulating the heating effect thereof.
- 15 As shown in Fig. 3 the portion of the pre-heating zone adjacent the entrance end of the furnace is enlarged and formed with a pair of lateral conduit passages J , to the bottoms of which are connected vertical passages J' . The passages J' discharge into a horizontal off-take flue J^2 , at the outer end of which is located an exhaust fan (not shown). The upper end of each vertical passage J' is provided with a damper plate J^3 for controlling the flow of gases. This arrangement provides a longitudinal circulation of heating gases from the burner section through the preheating zone and exhaustion of the gases to a suitable heat recovery device.
- 20 The cooling section b , as shown in Figs. 2 and 6, is provided with a series of vertically looped pipes K supported on each side wall of the furnace chamber. Each pipe has a cooling water inlet K' and an outlet K^2 .
- 25 The portion of the furnace chamber between the end of the burner section and the cooling section is decreased in width to minimize any flow of gases between the two sections of the furnace as shown in Figs. 1 and 5.
- 30 The cooling section b is provided with a series of vertically looped pipes K supported on each side wall of the furnace chamber. Each pipe has a cooling water inlet K' and an outlet K^2 .
- 35 The portion of the furnace chamber between the end of the burner section and the cooling section is decreased in width to minimize any flow of gases between the two sections of the furnace as shown in Figs. 1 and 5.
- 40 The cooling section b , as shown in Figs. 2 and 6, is provided with a series of vertically looped pipes K supported on each side wall of the furnace chamber. Each pipe has a cooling water inlet K' and an outlet K^2 .
- 45 The portion of the furnace chamber between the end of the burner section and the cooling section is decreased in width to minimize any flow of gases between the two sections of the furnace as shown in Figs. 1 and 5.
- 50 The endless carrier of my invention comprises longitudinal sprocket wheels C and C' located at opposite ends of the furnace. The sprocket wheel C is driven through a pair of gears C^2 in any suitable manner to move the carrier chain. At longitudinally spaced points along the chain cruciform shaped hangers B' are suspended, and each of which form the bearing for a pair of wheels B^2 adapted to roll on tracks F^6 supported by the frame F^6 . Depending from the lower end of each hanger is a hook B^3 for supporting a metallic carrier cage M within which the sheets of material are carried through the furnace.
- 55 Each cage M comprises a rectangular frame having upper and lower cross bars M' and M^2 , respectively, connected by a pair of vertical rods M^3 . The frame is detachably connected to a pair of hooks B^3 by a pair of

rods M^4 having a closed loop at their upper ends. A short U-shaped plate A^7 is supported on each rod M^4 and dips into a sand seal in the troughs A^8 to seal the top of the furnace chamber as shown in Fig. 4. The bar M' is provided at each end with a fixed projecting member M^5 having a recess M^6 therein. A U-shaped holding frame N of slightly greater width than the frame M has the lower ends of its leg portions pivotally mounted in forks formed in the outer ends of each bar M^2 as shown at N' . When the frame N is in its normal vertical position, the horizontal frame bar N^2 fits into the recessed portion M^6 of the projection M^5 .

The frame N is locked in this position by a pair of latch members O pivotally mounted at opposite ends of the bar M' adjacent the members M^5 . Each latch member O is formed with a downwardly projecting portion O' adapted to fit over the horizontal bar N^2 and hold the frame N in the vertical position. Each locking member is also provided with a beveled surface O^2 at the underside of its outer end. Each cage M is pivotally connected to the adjacent cages by a tongue member M^7 projecting from one end of the bar M^2 and fitting between a pair of tongues M^8 formed on the bar M^2 of the adjoining cage. The overlapping tongue portions are pivotally connected by a pin M^9 passing through aligned openings in the tongue members.

As shown in Figs. 1 and 10 a tripping bar P is mounted adjacent the driving sprocket C and provided with a beveled edge portion P' adapted to contact with the beveled surface O^2 of each pivoted locking member O . The inclination of the bar portion P' increases along its length in the direction of travel of the carrier whereby the latch member is raised to the position shown in dotted lines in Fig. 10 to release the frame N from the vertical position.

A guide plate Q is mounted on the loading platform D and provided with angular sections Q' and Q^2 extending towards the endless carrier. The section Q' is connected to one end of the bar P and is arranged to guide the frame N on its release from the locking position. The relative arrangement of the parts when the unlocked frame N is moving along the loading platform is shown in Fig. 7. The guide section Q^3 raises the frame N until the frame cams the latch O upwardly and the parts are again locked in position.

Substantially the same arrangement of the tripping bar and guide plates is provided at the opposite end of the furnace adjacent the unloading platform. In this arrangement the guide sections have a greater inclination and guide the frame N into the position shown in Fig. 8. The section Q^2 again restores the frame N to its locking position and

the cages remain locked throughout the return run of the carrier.

In the preferred mode of operating the apparatus described, the sheets of material to be heat treated are placed on the loading platform D and as the cages come into the position shown in Fig. 7 the sheets of material are placed in the cages with their side edge portion contacting with the bar M² of the cage. The sheet can be placed in the cages separately or in packs of two or more and simultaneously heat treated. The sheets are carried through the furnace in the vertical position at the desired rate for proper treatment and on emerging from the furnace are automatically discharged onto the unloading platform by the action of the tripping bar at that point. The cages are locked after being unloaded and returned to the entrance end of the furnace. Where it is desired to heat treat continuous strips of material, the material may be passed from a reel into the cages when in their loading position and taken off onto a second reel at the exit end of the furnace after the cages are unlocked.

My invention is not restricted to the longitudinal form of furnace and it can be built in circular form with the furnace occupying three-fourths of the circumference and the material handling and carrier driving means the remaining portion of the circle.

The invention disclosed is characterized by the simple and effective provisions for passing the sheet material through the furnace. The main advantages of supporting the sheets on their side edges are to prevent the surfaces of the sheets from being marred by contact with supporting rolls as usually occurs when sheets are passed through in the horizontal position and to provide a uniform heat treatment of all portions of the material in a furnace constructed as described. The portions of the conveyor and the cage exposed to the furnace temperatures are preferably made of light heat resistant metal or alloy rather than heavy sections of cast iron or steel. The loading and unloading provisions are especially simple in construction and effective in operation.

My invention is not restricted to the use of fuel burner nozzles in the side walls of the furnace chamber as the heating means therefore, and I contemplate using electrical heating means in the form of metallic, carbon or silicon carbide resistance elements mounted on the side walls of the furnace chamber in lieu of the burner nozzles. Such elements may be mounted on the floor of the chamber alone or in conjunction with other elements mounted on the side walls.

In Figs. 12, 13, 14 and 16, I have illustrated a modified form of sheet material holding means which is of considerably less size and weight than the carrier cages described thus reducing the accessory weight to be heated

and cooled during each passage through the furnace. In this construction each of the hooks B³ supports a vertical rod R having a transverse member R' at its lower end from which depend vertical rods R² and R³. Each of the latter has a metallic jaw block R⁴ and R⁵, respectively, secured to its lower end. The block R⁴ is formed with a ball R⁶ arranged to fit in a groove R⁷ in the block R⁵.

At the entrance end of the furnace a sheet is placed between the blocks R⁴ and R⁵ and the blocks passed between a pair of spring pressed rollers S and S' or any suitable mechanical means for causing the blocks to securely grip the sheet therebetween. As the blocks leave the rollers an automatic latch R⁸ mounted on the block R⁵ drops down over the block R⁴ to hold the blocks in the gripping position with the material therebetween. At the opposite end of the furnace the latch R⁸ is automatically released and the sheet material removed. The slight deformation of the upper edge of the sheet is removed during the cold rolling operation on the annealed sheet.

In Fig. 17 another type of holding means is shown for holding a metallic sheet at its upper edge. In this construction each pair of blocks R⁴ and R⁵ is secured together by a threaded bolt R⁹. The block R⁵ is provided with a recess T in which a pin T' is slidably mounted. The pin T' is arranged to pass through an opening T² in the block R⁵ and into a passage T³ in the block R⁴. A sheet of material is inserted between the adjacent faces of the blocks and the pin T' driven through the upper edge portion of the material. The sheet is thus positively held during its passage through the furnace. The resulting horizontal series of small holes in each sheet is not disadvantageous for some uses of the material.

While the annealing furnace shown is described as having a single line of carriers transporting the goods in one direction through the furnace and having the return run of the carrier externally of the furnace, my invention is not necessarily limited to that construction and the furnace may be constructed with twin carriers moving in the same direction through parallel heating chambers or a single line of carriers in a continuous loop moving in opposite directions through the furnace chamber.

In Fig. 13 is shown a single conveyor V supporting twin carriers V¹ and V² which move through parallel heating chambers V³ and V⁴, respectively, separated by a vertical wall V⁵. This arrangement can be modified for movement of the carriers in opposite directions through the furnace.

In Figs. 14 and 15, a single line of carriers W is shown in a continuous loop with both runs W¹ and W² of the conveyor within the furnace structure. In this arrangement the

sheets are carried during only one run of the conveyor or if desirable unloading and loading stations are arranged at each loop portion W³ and the material moved through the furnace chamber in opposite directions.

While in accordance with the provisions of the statutes, I have illustrated and described the best forms of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention what I claim as new and desire to secure by Letters Patent, is:

1. In a horizontal furnace having a furnace chamber therein, means for passing sheet material through said furnace chamber in a vertical plane comprising an endless conveyor and a plurality of material carrying cages supported from said conveyor, and means adjacent one end of the furnace for automatically opening said cages to receive the sheet material.

2. In a horizontal furnace having a furnace chamber therein, means for passing sheet material through said furnace chamber in a vertical plane comprising an endless conveyor and a plurality of material carrying cages supported from said conveyor, means for automatically opening said cages to receive the sheet material, and means for locking said cages after the material is placed therein.

3. In a horizontal furnace having a furnace chamber therein, means for passing sheet material through said furnace chamber in a vertical plane comprising an endless conveyor, a plurality of material carrying cages supported by said conveyor, each of said cages comprising a fixed and a pivoted frame member, and means for locking said pivoted frame member to said fixed frame member.

4. In a horizontal furnace having a furnace chamber therein, means for passing sheet material through said furnace chamber in a vertical plane comprising an endless conveyor, a plurality of material carrying cages supported by said conveyor, each of said cages comprising a fixed and a pivoted frame member, means for locking said pivoted frame member in a vertical position, and automatic means for unlatching said locking means to release said pivoted frame member.

5. In a horizontal furnace having a furnace chamber therein, means for passing sheet material through said furnace chamber in a vertical plane comprising an endless conveyor, a plurality of material carrying cages supported by said conveyor, each of said cages comprising a fixed and a pivoted frame member, means for locking said pivoted frame

member to said fixed frame member, means for releasing said locking means, and guide means for receiving said pivoted frame when said frame is released.

6. In a horizontal furnace having a furnace chamber therein, means for passing sheet material through said furnace chamber in a vertical plane comprising an endless conveyor, material carrying cages supported by said endless conveyor and each comprising a fixed frame, a second frame pivoted on said rigid frame and locking means for holding said pivoted frame in a vertical position, and a tripping bar arranged to contact with said locking means for raising said locking means to release said pivoted frame from its vertical position.

7. In a horizontal furnace having a furnace chamber therein, means for passing sheet material through said furnace chamber comprising an endless sprocket chain having one run extending above said furnace chamber, hangers secured to spaced points on said chain, a track mounted above said furnace chamber, track engaging wheels supported by said hangers, and sheet material carrying means detachably supported by said hangers.

8. In a horizontal furnace having a furnace chamber of relatively narrow width therein, means for passing sheet material through said furnace chamber comprising an endless chain having one run above said furnace chamber, a track positioned above said furnace chamber, track engaging wheels suspended from said chain, a plurality of sheet material carrying frames supported by said chain, and each of said frames being pivotally connected to the frames adjacent thereto, whereby adjacent frames are held in longitudinal alignment.

9. The combination with a horizontal annealing furnace comprising a longitudinally extending furnace chamber of relatively small width having heating and cooling sections arranged along the length of said chamber, of means for passing sheet material through the heating and cooling sections of said furnace chamber, in a vertical plane extending longitudinally of said furnace chamber, said means comprising an endless conveyor arranged above and externally of said furnace chamber, means for driving said conveyor, means connected to said conveyor for supporting said sheet material during its passage through the sections of said chamber, and means positioned adjacent the ends of said furnace for automatically actuating said material supporting means to arrange the latter in positions to receive and discharge said material.

10. The combination with a horizontal furnace having a horizontally elongated furnace chamber of relatively narrow width therein, of means for passing sheet material through said furnace chamber comprising an endless chain, and rectangular cages in which

said material is arranged in an upright position secured at spaced points on said chain, and means connecting and holding adjacent cages in longitudinal alignment.

5 11. The combination with a horizontal furnace having an elongated furnace chamber therein, of means for transporting sheet material in an upright position through said furnace chamber, said means comprising an endless conveyor mounted externally of said chamber and lockable means supported from said conveyor for engaging said sheet material, and stationary means adjacent the path of movement of said lockable means for automatically locking and unlocking the latter.

10 12. The combination with a horizontal furnace having an elongated furnace chamber therein, of means for passing sheet material to be heat treated through said chamber with its main surfaces exposed to the sides of said chamber, said means comprising an external support moving longitudinally above said chamber, a two section carrier secured to said support, and locking means holding said carrier sections together, and means adjacent each end of said chamber for automatically actuating said locking means to open and close said carrier.

15 13. The combination with a horizontal furnace having a horizontally elongated furnace chamber of relatively narrow width therein, of means for passing sheet material through said furnace chamber in an upright position, and means for uniformly heating said material during its passage comprising an upper and lower row of fluid fuel burners in said furnace chamber at each side of said material, a refractory baffle adjacent the discharge end of the fuel burners in said 20 upper row and a recessed block adjacent the discharge end of the fuel burners in said lower row, whereby the combustible mixture discharged from said fuel burners is deflected upwardly in said furnace chamber.

25 45. Signed at Cleveland, in the county of Cuyahoga and State of Ohio, this third day of April, A. D. 1928.

PAUL A. MEEHAN.
